FURNACE GRATE

Frederic Helmick, Fairmont, W. Va.

Application August 26, 1936, Serial No. 98,024

9 Claims. (Cl. 126—163)

This invention relates to certain new and useful improvements in grate bar constructions, especially designed for use in furnaces having automatic stokers and as illustrated in the drawings 5 show a plurality of grate bars assembled in an extension frame of an underfeed stoker for boiler furnaces.

Another object of my invention is to provide a plurality of grate bars when assembled with maximum zig-zag air spaces between and through the 10 grate bars from the upper to the lower end of the stepped portion of the grate bars.

A still further object of the invention is to increase the air passages between and through the 15 assembled grate bars to increase the distribution of air which is accomplished by having air passages from top to bottom of the stepped portion of the grate surface of a zig-zag formation.

A still further object of the invention is to provide the bars with strengthening flanges or ribs 20 which form shelves that retard the sifting of the fine ashes through the air spaces between the assembled grate bars into the air channel whereby any ashes that sift through will be blown back 25 from the wind box through the air outlets into the combustion chamber of the furnace.

A still further object of the invention is to provide a grate bar so constructed that when a plurality of these bars are assembled that the air 30 passing through the air outlets will contact more forcibly with those portions of the grate bar exposed to the greatest heat, thereby increasing the life of the grate bar.

Other and further objects and advantages of 35 the invention will be hereinafter set forth and the novel features thereof defined by the appended claims.

In the drawings,

Figure 1 is a perspective view of a plurality of 40 grate bars constructed in accordance with my invention assembled on an extension frame, the bars being broken away to show the construction of the frame;

Figure 2 is a front elevation of a grate bar assembly constructed in accordance with my invention, partly broken away;

Figure 3 is a top plan view, partly broken away;

Figure 4 is a vertical section through the extension frame showing the grate bar in elevation;

Figure 5 is an inverted plan view of one of the 50 grate bars;

Figure 6 is a longitudinal section through one of the bars; and

Figure 7 is a section taken on line 7—7 of Figure 55 6.

In the embodiment of my invention as herein shown, I show a plurality of interlocking hollow 60 grate bars A assembled in an extension frame B which is of conventional type and is adapted to

be used in underfeed stokers for boiler furnaces. The grate bars A are constructed exactly alike with the exception of the end bars A' and the description of one of the intermediate bars will be sufficient for all. These bars are assembled in 5 an extension frame to form a grate with its upper face in downwardly trending step formation to provide a plurality of air outlets from the wind boxes extending at an angle to the longitudinal center of the respective bars to more equally distribute the air into the fuel bed overlying the grate, 10 thereby increasing the combustion.

The hollow grate bars A have a body portion 15 which is substantially inverted U-shape in cross section and zig-zag in formation having a horizontally disposed flat portion 1 at its upper end, the lower end being stepped to form tread portions 2 and riser portions 3, the lower riser portion 4 being provided with spaced air outlets 5 formed by a web 6 which extends rearwardly and downwardly as shown for deflecting the air through these outlets. One side wall of each step 4 is provided with a lateral and rearwardly extending flange 7 which extends between flanges 8 and 9 formed on the opposite side wall of the adjacent bar, the flange 9 being an extension of the tread 10 and having a rearwardly and downwardly extending portion 11.

The riser of each step is cut out between the legs 30 of the inverted U shaped body to form an air outlet 12 extending at an angle to the longitudinal center of the bar, a web 13 being disposed between the legs of the inverted U portion of the body of the bar which extends rearwardly and downwardly to deflect the air from the wind box through the 35 outlet and against the tread. One edge of the tread 2 of each step is extended laterally as shown at 14 and then rearwardly and downwardly at an angle to the tread to form a lateral flange which extends between the flanges of the adjacent bar so that when a plurality of these grate bars are 40 assembled, the flanges along one side of the grate bar extend between the flanges of the adjacent grate bars to provide air outlets 18 from the wind box to more equally distribute the air to the grate 45 and to provide means for blowing back any ashes sifting between the respective grate bars. It will be noted that when a plurality of these grate bars are assembled that the air outlets formed in the riser of one step extend obliquely in one direction 50 and in the next step obliquely in the opposite direction.

The outside grate bars A' have their inner edges corresponding in shape and design with the adjacent edge of the adjacent grate bar. The outside 55 edges of the outside bars A' are formed to conform with the flat sides of the frame B and are provided with flanges A².

The flat portion 1 of the grate bars have overhanging flanges 16 along one edge, the upper faces 60

of which are flush with the flat portion 1, the opposite edge being cut away from a point X to the rear edge thereof to provide a flange 17 upon which rests the rear portion of the adjacent flange 16 of the adjacent grate bar when these bars are assembled. Each tread of the grate bar has a beveled front edge and the tread is extended between the legs of the U to form the web 13 which extends downwardly at its rear end so as to deflect the air from the wind box upwardly against the under sides of the tread. The under side of the beveled portion of the tread is in a plane parallel with the beveled portion to deflect the air downwardly on the adjacent tread through the fuel thereon.

The grate bars are provided with lugs 19 embracing transverse bars 20 of the frame B and with notches 21 into which extend the upper ends of vertically disposed bars 22 of the frame B. The outside bars A' are secured to apertured threaded lugs 23 by bolts 24, the particular manner of mounting these bars in an extension frame of an underfeed stoker can be changed without departing from the spirit of my invention.

The under side of the lower ends of the grate bars are cut to provide shoulders 25 which rest on shoulder 26 formed on the lower end of the frame B and when a plurality of these grate bars are assembled on an extension frame, a grate is produced which is very strong and durable and in which the air from the wind box is equally distributed to the combustion chamber.

In constructing a grate in accordance with my invention, each of the intermediate hollow grate bars is of a stepped longitudinal zig-zag formation with a body portion substantially inverted U shape in cross section with alternately extending flanges from the treads of the steps as it will be noted that the tread of the lower step is extended to the left to form a flange and the tread of the next step extended to the right to form a flange, this being carried out throughout the length of the grate bar whereby I not only provide outlet passages extending through each grate bar but to each side, each outlet passage having a deflector for deflecting the air so as to more equally distribute the air to the bed of fuel in the grate.

From the foregoing description it will be seen that I have produced a hollow grate bar zig-zag in formation with a body portion substantially inverted U shape in cross section having a stepped portion in which the risers of the steps are provided with air outlets having deflectors for deflecting the air against the under side of the tread and when a plurality of these bars are assembled with their flanges interlocked, additional air outlets are formed between the respective grate bars having deflectors formed by the rearwardly extending portion of the flanges for deflecting the air against the lateral extending portions of the treads whereby I am able to more equally distribute the air from the wind box to cause the same to be forced against those portions of the grate bar which are subjected to the greatest amount of heat and at the same time I am able to collect any fine ashes sifting through the spaces between the grate bars so that these ashes will be blown back to the combustion chamber.

70 What I claim is:

1. A grate composed of a plurality of interlocking hollow grate bars, each bar having a stepped longitudinal zig-zag formation and an open bottom, the riser of each step being provided with an air outlet.

2. A grate bar formed of a plurality of interlocking hollow grate bars, each grate bar having a stepped zig-zag longitudinal formation and an open bottom, the riser of each step being provided with an air outlet, the tread of one step being extended outwardly in one direction and the tread of the adjacent step being extended outwardly in the opposite direction to provide flanges for spacing the bars apart to provide additional air outlets.

3. A grate bar formed of a plurality of interlocking hollow grate bars, each grate bar having a stepped zig-zag longitudinal formation and an open bottom, the riser of each step being provided with an air outlet, the tread of one step being extended outwardly in one direction and the tread of the adjacent step being extended outwardly in the opposite direction to provide flanges for spacing the bars apart to provide additional air outlets, the bars being provided with deflecting portions for deflecting the air through the outlet openings.

4. A grate bar having a stepped zig-zag longitudinal formation, the riser of each step being provided with an outlet, the outlet of one tread extending at an angle to the outlet of the adjacent tread.

5. A grate comprising a plurality of interlocked hollow grate bars, the intermediate grate bars having a stepped zig-zag longitudinal formation and an open bottom, the alternate treads of said steps being extended laterally and rearwardly to provide flanges for spacing the risers of said steps apart to provide air outlets, the riser of each step being provided with an air outlet.

6. A grate of the kind described composed of a plurality of hollow grate bars arranged within a frame, each grate bar having a longitudinal step zig-zag in formation and an open bottom, the treads of each step being provided with lateral flanges for spacing said grate bars apart to provide outlets between the respective grate bars, the riser of each step being provided with an air outlet.

7. A grate of the kind described adapted to be arranged over a wind box formed of a plurality of hollow grate bars, each grate bar having a longitudinal stepped zig-zag formation and an open bottom, the treads of said steps being provided with lateral flanges for spacing said bars apart to provide air outlets, the riser of said steps being provided with air outlets, the air outlets of the riser extending at an angle to one another.

8. A grate of the kind described adapted to be arranged over a wind box formed of a plurality of hollow grate bars, each grate bar having a longitudinal stepped zig-zag formation and an open bottom, the treads of said steps being provided with lateral flanges for spacing said bars apart to provide air outlets, the risers of said steps being provided with air outlets, the air outlets of the risers extending at an angle to one another, said bars being provided with rearwardly and downwardly extending portions to form deflectors for deflecting the air against the under side of the treads of said steps.

9. A grate formed of a plurality of closely assembled hollow grate bars having a longitudinal stepped formation and an open bottom, the riser of each step being provided with an air outlet, the outlet of one riser extending at an angle to the outlet of the adjacent riser of said bar.
